(57) **CLAIM**

The ornamental design for a jewelry storage and display device, as shown and described.

DESCRIPTION

FIG. 1 is a frontal perspective view of a jewelry storage and display device in accordance with a first embodiment of the invention;

FIG. 2 is a front view of the jewelry storage and display device of FIG. 1;

FIG. 3 is a rear view of the jewelry storage and display device of FIG. 1;

FIG. 4 is a left side view of the jewelry storage and display device of FIG. 1;

FIG. 5 is a right side view of the jewelry storage and display device of FIG. 1;

FIG. 6 is a top view of the jewelry storage and display device of FIG. 1;

FIG. 7 is a bottom view of the jewelry storage and display device of FIG. 1;

FIG. 8 is a frontal perspective view of the jewelry storage and display device of FIG. 1 depicted in an environment of possible use;

FIG. 9 is a frontal perspective view of a jewelry storage and display device in accordance with a second embodiment of the invention;

FIG. 10 is a front view of the jewelry storage and display device of FIG. 9;

FIG. 11 is a rear view of the jewelry storage and display device of FIG. 9;

FIG. 12 is a left side view of the jewelry storage and display device of FIG. 9;

FIG. 13 is a right side view of the jewelry storage and display device of FIG. 9;

FIG. 14 is a top view of the jewelry storage and display device of FIG. 9;

FIG. 15 is a bottom view of the jewelry storage and display device of FIG. 9; and,

FIG. 16 is a frontal perspective view of the jewelry storage and display device of FIG. 9 depicted in an environment of possible use.

The broken lines shown in the drawings depict portions of the jewelry storage and display device that form no part of claimed design. The hangers seen in broken lines in FIGS. 8 and 16 are environmental and form no part of the claimed design.
